SYSTEM OF PACKAGING

I. Lawrence Lesavoy, Allentown, Pa.

Application August 8, 1941; Serial No. 406,010

31 Claims. (Cl. 66—1)

This invention relates to a system of packaging, and particularly to an apparatus for continuously fabricating bags, dispensing selected products into the bags and sealing the filled bags.

In large scale packaging operations, preformed containers are generally employed to receive the product to be packaged from a suitable feeding or conveying apparatus. When such containers are in the form of boxes, they are space-consuming, expensive and necessitate the employment of costly and intricate sealing methods; and where such boxes are purchased in collapsed condition, they require individual handling to place them in condition to receive the goods. When the containers are in the form of bags, they are generally difficult to handle because of their limp condition. Furthermore, such bags contain long lateral seams in view of the fact that they are made from flat lengths of material which must be formed and sewed together. These seams are unsightly, and besides, they reduce the strength of the bag because of its tendency to open at the seams when loaded. And in most of the packaging methods heretofore employed, especially where large bulks are handled, the steps of fabricating the container, setting it up, dispensing the product to be packaged and sealing the filled container, are separately performed in successive stages, being both time-consuming and expensive. And should the various steps not be performed in perfect synchronism, there will be a bottleneck and a consequent delay all along the line.

It is within the contemplation of this invention to avoid the aforesaid shortcomings in large-scale packaging operations by providing a system of continuously forming containers as the product to be packaged is being dispensed, and automatically sealing and separating successive filled containers.

In the preferred method of my invention, the container is automatically produced on a knitting machine in the form of a seamless knitted bag, and predetermined quantities of the product are supplied to successive bags as they are being made, whereafter the bags are sealed at top and bottom only. And in this aspect of my invention it is an object to enable the dispensing, sealing and bag separating mechanisms to be coactively associated with the knitting apparatus, so that the timing of said mechanisms will bear a predetermined relation to the size and proportions of the bags knitted by the machine.

It is another object of my invention to enable bags of several layers to be simultaneously knitted, thereby producing containers combina-

tively adapted to hold fine-grained contents or contents of great weight.

And another object of this invention is to enable packages produced by this apparatus to be automatically identified by labels or printed impressions.

Other objects, features and advantages will appear from the drawings and the description hereinafter given.

10 Referring to the drawings:

Figure 1 is a fragmentary front elevation, showing partially in section, the apparatus constituting my invention.

Figure 2 is a section of Figure 1 along line 2—2.

Figure 3 is a section of Figure 1 along line 3—3.

Figure 4 is a fragmentary development of the actuator cam mechanism for operating the gathering mechanism of my invention, the view being taken substantially along line 4—4 of Figure 1.

15 Figure 5 is a sectional plan view of Figure 1 taken substantially along line 5—5, the dot-dash lines indicating the projected position of the gathering mechanism.

Figure 6 is a sectional plan of Figure 1 taken substantially along line 6—6 thereof, the view showing only the cutting means.

Figure 7 is a fragmentary plan view of the stapping mechanism shown in its projected position after having formed a closure for the casing.

20 Figure 8 is a fragmentary vertical sectional view of my invention showing one method of applying a label between the walls of the casing.

Figure 9 is a diagrammatic view showing the electrical connections employable with my invention.

25 Figure 10 is a perspective view of one of the gathering segments and its cam follower, and

Figure 11 is a fragmentary vertical section of a label marking device adapted for association

30 with my invention.

The drawings illustrate an embodiment of my invention wherein two coacting knitting units are arranged to simultaneously knit two concentric tubes of fabric which are formed into a double-walled bag for receiving the product to be packed. Although this embodiment is preferred, my invention also contemplates the employment of a single knitting machine for producing single-walled bags adapted to receive the product by substantially the same instrumentalities employable with the double-walled structure.

35 In the form illustrated, the cylinders 10 and 11 of the upper and lower knitting machines, respectively, are surrounded by and operatively associated with cam rings 12 and 13, respectively.

A plurality of posts 14 and 15 support the upper and lower yarn stands 16 and 17, respectively, so that upon an operative rotation of said cam rings and stands, the yarns 18 and 19 will be fed to the needles 20 and 21 of the cylinders to form tubular casings of knitted material 22 and 23 extending downwardly within the cylinders. The detailed construction of the needles and needle-elevating and depressing mechanism is not shown in view of the fact that they are of conventional structure and are well-known to those skilled in the art.

It is to be further observed that the two said cylinders 10 and 11 are coaxially arranged, and that the base 24 of the lower cylinder serves to support the base 25 of the upper cylinder through the medium of the posts 26. The cam rings 12 and 13 are coaxially associated with each other through the medium of bevel gears 27 and 28, the shafts 29 and 30 and the transmission line 31, said transmission line being preferably either an endless chain or belt and pulley arrangement. Although either of said shafts 29 or 30 may be connected with the source of motive power, the drawings illustrate shaft 29 as being so connected. According to the design illustrated, the gears 27 and 28 are revolvable at the same speeds, to produce identical knitting speeds for both the upper and lower cylinders. Should it however be desired to change the relative knitting speeds of both machines, so as to produce a double-walled bag with the inner wall 22 containing a different arrangement of wales and courses than that of outer wall 23, it is within the contemplation of my invention to so modify the transmission mechanism 31, in conventional manner well-known in the art, as to effect the desired speed ratio between shafts 29 and 30 and consequently between the knitting speeds of the upper and lower cylinders.

Centrally disposed within the cylinders 10 and 11 of the coating knitting machines is the hopper 32 extending downwardly from a point above the uppermost yarn stand and parts carried thereby, to a point preferably well within the lower cylinder 11. In the structure shown in the drawings, the hopper contains the outlet portion 33 terminating at a point substantially at the level of the cam ring 13; but it is to be understood that the position of said outlet portion can be modified to suit particular design requirements. It will also be observed that the upper yarn stand 16 is rotatably associated with the hopper 32 through the medium of the ball-bearing arrangement 16a in rotatable engagement with the outer cylindrical surface of the hopper. In this manner the hopper serves to help support the said yarn stand.

At the top of the hopper 32 is a floor 34 serving as a support for the dispensing mechanism constituting a part of my invention. Slidably mounted upon said floor is the dispenser or valve member 35 containing two compartments 36 and 37 separated by a wall 38. Extending into both compartments from said wall is the gate 39 which, in the preferred form, contains two downwardly sloping surfaces 40 and 41, said valve being slidably movable on floor 34 so as to partially obstruct the inlet opening 42 at the top of the hopper 32. The said dispenser 35 has in the lateral wall 43 thereof two apertures 44 and 45, each of these apertures being adapted to be moved into registry with corresponding apertures 46 and 47 of the conveyor apparatus 48, upon an

operative oscillation of the dispenser, in a manner to be more fully hereinafter described.

The said conveyor apparatus 48, in the particular form of my invention illustrated, comprises a cylindrical tube 49 containing therein a conventional helical or screw type of conveyor 50. The conveyor tube 48 is offset with respect to the hopper 32 and dispenser 35, and contains two conduits 51 and 52 terminating in the said apertures 46 and 47. The said conduits 51 and 52 terminate in flange 53 in slidable abutment with the flange 54 of the dispenser member 35. The arrangement is such that should it be necessary to gain access to the interior of the knitting machine cylinders, the hopper 32 can be withdrawn upwardly, after being operatively detached from the dispenser 35, without interfering with the conveyor mechanism 48.

Pivottally attached to the dispenser 35 at 55 is the lever 56 mounted upon the hopper 32 at 57; and pivotally connected to lever 56 at a point intermediate its ends is the link 58 operatively connected to the crank 59 associated with the reduction gear 60 and the motor 61. The arrangement is such that upon an operative rotation of the motor 61 for a predetermined interval, the crank 59 will be rotated through an arc of about 180 degrees to thereby actuate the link 58 and lever 56 to the right, thus producing a 20 slidable movement of the dispenser 35 also to the right. It will be observed that when the said dispenser 35 is in its extreme left position, the aperture 44 thereof is in registry with the aperture 46 associated with conveyor 48, and when 25 the dispenser is in its extreme right position, the aperture 45 thereof will be in registry with the corresponding aperture 52 of the conveyor tube. The dispenser 35 also carries with it the plate 62 which extends over and serves as a closure 30 for aperture 47 of the conveyor when the dispenser is in its left position, and which also extends over and serves as a closure for the aperture 46 of the conveyor when the dispenser 35 is in its extreme right position.

45 The said hopper or chute 32 contains, in the preferred form thereof, the baffles 63 to intercept and break the fall of the material being discharged. The lower portion of the hopper also contains, extending downwardly therefrom, and 50 surrounding the said outlet portion 33, the inwardly curved forming base and guide 64. In the preferred form of my invention, the said guide 64 is disposed circumferentially about the central axis of the cylinders, and is in the form 55 of a hollow, substantially conical shell. The wall of member 64 is also preferably resilient so that it exerts a slight outward pressure against the tubes of knitted material. A plurality of friction segments 65, of resilient construction, are disposed about said member 64, the relationship 60 between the member 64 and segments 65 being such as to permit the knitted tubes 22 and 23 to pass downward therebetween and be slightly frictionally retarded thereby against the downward pull operatively exerted upon said tubes. In this manner the members 64 and 65 will create a slight drag or resistance to the downward pull and thereby obviate the danger of any excessive tension being induced within the knitted tubes 22 and 23 extending down from the knitting levels.

65 The lower outlet portion of hopper 32 is provided with two swingably mounted closure members or gates 66 and 67, these members being pivotally mounted at the axis 68 at the termi-

nal portion 69 of the said hopper. Each of the gates has affixed thereto a lug 70, these lugs extending outwardly in an inclined direction as shown clearly in Figure 1. In underlying engagement with said lugs are the terminal portions of the actuator 71 containing a bar 72 with a loop member 73 extending transversely between the said lugs. Affixed to said actuator is the solenoid core 74 movable vertically within the solenoid coil 75 when the circuit through said coil is operatively closed. Upon such a closing of the circuit, the said core 74 will be drawn upwardly, to carry the actuator 71 and loop 73 upwardly also. The lugs 70 will thereby be engaged by loop 73 and the gates 66 and 67 will be pivotally opened to the dot-dash position shown in Figure 1. When this occurs the contents within the outlet portion 33 of the hopper will be discharged in a manner to be more fully hereinafter set forth.

At a predetermined level below the forming guide 64 is the gathering mechanism 76 containing a number of arcuate segments 77 (see Figure 10) circumferentially disposed about the outer tube of knitted fabric 23, these segments being adapted to move inwardly radially in such a manner as to embrace and draw together the concentric knitted fabric tubes 22 and 23 to form a bag closure, hereinafter to be described. The said segments 77, in the form of my invention illustrated, are in overlapping arrangement, each being adapted to partially embrace the bag and to force the engaged portion thereof radially inwardly when the assembly of segments is operatively contracted. The segments are each provided with a rod 78, shown as being of substantially square cross-section, and extending radially outwardly with respect to the cylinders of the knitting machines. Preferably at the outer portions of each of said rods is follower pin 79 extending downwardly into a slot 80, constituting a cam path, within the cam plate 81. The said cam plate 81 is horizontally disposed and slidably mounted within annular support 82 and wall 83.

An actuator cam ring 84 is slidably mounted on bed plate 85, and contains an annular rack 36 in threaded engagement with gear 87. The cam ring 84 carries on the inner surface thereof the lug 88 which, upon an operative rotation of said cam ring, is adapted to engage the plate actuator or slide pin 89 extending through aperture 90 in cam plate 81, said pin being slidably movable vertically therein within the limits of stops 91 and 92. The said slide pin 89 contains an inclined surface 93 adapted to engage the correspondingly inclined surface 94 of the abutment member 95. When the pin 89, moving under the influence of lug 88, reaches member 95, the surface 94 engages surface 93, whereby the pin 89 will be elevated to a point completely out of engagement with lug 88. Hence after pin 89 reaches member 95, the lug 88 is no longer in engagement therewith and cannot operatively effect a movement of plate 81.

When the said actuator pin 89 is caused to move by lug 88 in the direction of the arrow (Figure 4) the cam plate 81 will be moved a corresponding distance in the same direction. This causes the follower pins 79 to move inwardly (towards the cylinder) within the slots 80, thereby causing an inward radial movement of the rods 78 and consequently the segments 77 to produce a gathering together of the tubular fabric. After the actuator pin 89 has be-

come disengaged from lug 88, the springs 96 will cause a retraction of cam plate 81 to its original position, thereby causing an outward return movement of the pin followers 79 within slots 80 to their original positions. This movement obviously causes a retraction of the gathering segments 77 from their projected positions.

It will be observed that a portion 97 of each slot 80 extends for a predetermined distance along a circumferential path. The purpose of this is to hold the follower pins 79, and consequently the gathering segments 77, in their projected positions while a stapling or sealing operation is being performed, in a manner to be hereinafter described.

The actuator cam ring 84 contains on its inner surface cams 98 and 99, the former being adapted to actuate the stapling head 100 and the latter the complementary anvil 101. The stapler head 100 is carried by lever 102 pivotally mounted at 103, the arm 104 terminating in a roller 105 constituting the follower for the cam 98. Similarly, the anvil head is carried by a lever 106 pivotally rotatable at 107, the arm 108 of the lever terminating in a roller 109 constituting the follower for the cam 99. The stapler head 100 contains therein the plunger 110 in engagement with the expandable toggle linkage 111; and connected to the said linkage at 112 is the plunger lever 113 the outer terminal 114 of which is engageable with the cam 115 affixed to the stationary framework of the machine.

Upon an operative rotation of cam ring 84, the said cams 98 and 99 will cause the staple and anvil heads 100 and 101 respectively to move inwardly, against the action of springs 110 and 111. The plunger lever 113 is carried along by this movement until it is engaged by the cam 115, so that at the end of the movement of lever 102 there will be a shift in the relative positions of levers 102 and 113. The lever 113 will actuate the linkage 111 and consequently the plunger 110 downwardly to produce a stapling operation in conventional manner. Figure 7 illustrates the completion of this stapling or sealing operation, the wire staple 112 being forced by the cooperative action of the stapling head 100 and anvil 101 to embrace the gathered-together portion of bag 113. Further details of the stapler are not herein described, inasmuch as it can be of any conventional structure known to the art.

It will be observed, by referring to Figure 1, that below stapling head 100, diagrammatically represented by a rectangle, is another stapler 114, both of the staplers flanking the gathering mechanism 76, one being thereabove and the other therebelow. The said stapler 114 is operated precisely in the manner of stapler 100, preferably by cams similar to cams 98 and 99 and disposed directly therebelow. It is thus apparent that during the operative rotation of cam ring 84, both the upper and lower staplers are simultaneously brought into action, at spaced levels, so as to produce sealed closures 115 and 116 (see bottom of Figure 1). The upper sealing staple at 115 constitutes the bottom closure of the upper bag, and the lower staple at 116 constitutes the top closure of the lower bag.

A cutting device for separating the upper and lower bags between closures 115 and 116 is also operated by the actuator cam ring 84. At another portion of the inner surface of said cam ring 84 is the cam 117 engageable with the roller 118 of the lever arm 119. This arm 119 is pivotally connected at 120 to sleeve 121, the lower

terminal of which carries the bell crank 122; and the terminal portion 123 of the bell crank carries the rotatable circular knife 124. It is thus apparent that upon an operative engagement of cam 117 with follower 118, the sleeve 121 will be rotatably actuated to cause an arcuate movement of bell crank 122, thereby bringing the knife 124 into engagement with the region between closures 115 and 116. In order to effect a rotary cutting movement of the knife, the cam ring 84 is provided with a segmental rack 125 engageable with gear 126. This gear is affixed to shaft 127 extending through the sleeve 121 and terminating in a pulley 128. Operatively connecting this pulley with pulley 129 is the belt 130, the pulley 129 being operatively connected with the shaft 131 upon which the knife is mounted. Upon an operative engagement of the gear 126 with rack 125, the knife 124 will thus be rotatably actuated, during the period of such engagement, to effect the desired cutting action. The combined action of cam 117 and rack 125 on the cam ring, in proper timed relation, will hence produce a severance of two adjacent bags.

It is obviously important that the operative sealing of the bags by the stapling mechanism be performed at certain predetermined intervals, depending upon the amount of material to be packaged and the proportions of the bag. Inasmuch as the bag consists of knitted courses and wales, a definite and predetermined relationship can be established between the knitting mechanism and the actuating mechanism for the gatherer 76, the staplers 100 and 114 and knife 124. A drive for the actuating mechanisms is hence taken off the bevel gear 28 which controls the rotation of knitting cam ring 13 and which co-acts with corresponding bevel gear 21 controlling the action of knitting cam ring 12. The shaft of one of these bevel gears, preferably shaft 30 of gear 28, contains a pin 132 adapted for engagement with the teeth or cogs 133 of the cog wheel 134. The said wheel 134 is connected in conventional manner through a transmission arrangement to gear 87, said transmission including the gears 135 and 136. The number of cogs on wheel 134 and the ratio of the various gears should be made such as to conform with the particular case. It is obvious that the design should be such that the cam rings 12 and 13 will rotate many times before the gatherer, staplers and cutter will be actuated, inasmuch as each rotation of said cams about the knitting cylinder produces one course of knitting. Upon calculating the number of courses to produce a bag that will accommodate the desired contents and also provide room for a suitable closure, the total number of turns of cam rings 12 and 13 can be made to bear a predetermined relationship to the turns of the actuator cam ring 84 controlling the action of said gatherer, staplers and knife. Should it be desired at any time to alter the size of the bags, all that need be done is to substitute a suitable transmission mechanism between shaft 30 and lower cam ring 84, such transmission mechanism preferably containing the elements set forth in the drawings.

Mounted on the shaft of gear 27 is the electrical timing mechanism 137 which is adapted to set into operation the said motor 61 for operating the oscillating dispenser 35 and solenoid 75 for actuating the closure mechanism at the bottom of the hopper 32, as well as for operating any other necessary electrical device operatively associated with the apparatus. Figure 9 gives a

diagrammatic illustration of this timing mechanism, which includes a rotatable drum 138 mounted on the shaft of gear 27, containing thereon a number of contacting elements 139, 140 and 141. The drum also carries a metallic contactor ring 142. The various contacting elements are adapted for operative engagement with the brushes 143, 144, 145 and 146, respectively. These brushes are adapted to engage the corresponding contact elements to close the circuit through the various electrical devices forming part of this apparatus. For example, when brush 144 engages contact 140, the circuit through the solenoid 75 is closed; when brush 143 engages contact 139, the circuit through the motor 61 is closed; and when brush 145 engages contact 141, the circuit through motor 147, to be later referred to, is closed. The position of contacts 139 and their dimensional proportions can be varied to suit particular requirements, and the circuit can thus be closed at a predetermined time for any predetermined interval. It is important to note that inasmuch as the electrical timing mechanism 137 is connected to gear 87, it is operatively associated with the knitting machine cam rings 12 and 13, so that the devices actuated thereby can bear a predetermined relationship either to the knitting operations or the length of the bag formed by the machine.

In the operation of this apparatus, any given product can be fed into the conveyor tube 48 so that predetermined quantities thereof may be conducted to the hopper 32. For many types of material, the screw type of conveyor 50 will be suitable, such as for granular material or material consisting of relatively large sized pieces, such as fruits and vegetables. It is of course obvious that if the particular material to be packaged is not suitable for operative use with a screw type of conveyor system, as might be the case with mailing matter and other bulk material, a conventional hopper or other feed system may be employed as convenience might dictate.

In the screw type of conveyor illustrated, the material is moved through tube 48 towards the aperture 46 in registry with aperture 44 of the dispenser mechanism. The material will consequently be discharged into compartment 36 of the dispenser 35. Inasmuch as the other aperture 47 of the conveyor tube 48 is covered by plate 62, none of the contents can be ejected at this point. However, one or more additional devices according to this invention can be operatively associated with other portions of the conveyor tube 48, so that a continuous operation of the conveyor system can be permitted without any interruption whatsoever.

It will be observed that compartment 37 is empty while compartment 36 is full. This is because the contents of compartment 37 have dropped through opening 47 into the hopper 52, such contents being shown at the lower closed outlet portion 33 of the hopper 32. The two knitting machines are constantly being operated and are continuously producing tubes of fabrics 22 and 23. At certain predetermined times, the solenoid core 74 will be actuated under the influence of the timing mechanism 137 above described, to cause an upward movement of the actuator 71 and an opening of the gates 66 and 67. The contents within the hopper 32 will then be discharged into the bottom of the bag, which has previously been sealed by the action of the gatherer 76 and staplers 100 and 114. It should be observed that after the material had passed through the gates

66 and 67 and the circuit through the solenoid 75 opened, the gates will close under their own weight, to provide a closure for the hopper ready for the next operation.

In timed relation with the above described action, the circuit through the motor 61 is similarly actuated by the timing mechanism 137, to cause a slideable movement of the dispenser 35 to the right. This will bring compartment 36 above opening 42, to deposit the contents into the hopper 32 in the manner above set forth. The aperture 45 however will be in registry with the opening 47 of the conveyor system, so that the product to be packaged will now be deposited through aperture 45 into compartment 37. In this manner the dispenser 35 is slideably oscillated to alternately receive and discharge the materials to be packaged.

It will be observed that the forming guide 64 is inwardly curved. This serves the function of guiding the tubes 22 and 23 constituting the walls of the bag being formed, inwardly towards the center during the gathering operation, thereby aiding in forming the bottom portion of the bag in a neat and presentable manner.

After the gathering and stapling operation has been completed and the material deposited into the sealed bag, the weighted bag serves to provide the necessary downward pull upon the tubes of fabric being knitted by the machines. This eliminates other mechanical devices conventionally employed to effect such a pull. However, as aforesaid, the dragging action of members 65 and 64 against the downwardly moving tubes 22 and 23 produces a sufficient resistance to such downward movement as to prevent any unduly excessive pull. The amount of friction afforded by the members 64 and 65 can be predetermined to suit the particular conditions, and can be governed by the tensile strength of the fabric, the closeness of stitching, and the weight of the contents within the bag.

It is only after the weighted bag has served its function above described, that it is preferred to effect the severing operation between the upper and lower bags. It is for this reason that the knife 124 is disposed at a predetermined level below the gathering mechanism 76. After the lower bag is severed, it is only the contents of the upper bag 148 that serves to provide the downward pull.

In order to properly identify the contents, a system of labelling may be employed. Figure 8 shows one form thereof in which a magazine 149 contains a stack of labels 150 adapted to slide downwardly through an aperture 151 sufficiently wide to permit no more than one such label to move therewith. A motor 141, operatively connected as aforesaid to the timing mechanism 137, is connected by suitable reduction gears 152 to the friction wheel 153 which engages, through an aperture 154 in the base of the magazine, the lowermost label and ejects it through said opening 151. This ejected label passes over guide 155, and then in between adjacent portions of the knitted tubes 22 and 23. The arrangement is hence such that as the two tubes converge together at the lower cylinder, an identifying label is deposited therebetween at predetermined intervals. It is understood that this particular arrangement is adaptable for use with large and coarse stitching so as to permit any written subject matter on the labels to be readily visible.

In the event however only a single tube is 75

knitted to provide a single-walled bag, or in the event it is desired to apply a printed impression to the outer surface of the double-layer bag above described, the stamping mechanism of Figure 11 may be employed. The segment 65a contains an aperture 156 adapted to receive therethrough the stamp 157 pivotally movable from an inoperative to an operative position as shown. Linkage 158 operatively connected to the stamp 10 is associated with actuator ring cam 84 through the medium of member 159. With each revolution of cam 84, the member 159 will thus actuate the stamp into the operative position against the outer wall 23 of the bag being formed.

15 It is thus apparent that with the use of the system above described, various types and grades of material can be conveniently and continuously packaged and, if desired, identified, in bags formed of knitted materials containing no lateral 20 seams whatsoever. This apparatus is adapted to knit a double-walled bag as illustrated, a single-walled bag, or a multiple-walled bag of any desired number of layers. Where two or more knitting machines are cooperatively employed to 25 form a multiple-walled knitted tube in accordance with my invention, not only is such a fabric of greater strength than a single-walled fabric, but it may be made with the outermost and innermost exposed surfaces of predetermined texture 30 and designs. This is the equivalent of a two-faced fabric hitherto unknown in the knitting industry.

It is of course understood that other additional forms and modifications of the apparatus 35 and adaptations of the method constituting this invention can be employed beyond and in addition to those hereinbefore described, all within the scope of the appended claims.

What I claim is:

40 1. In a packaging apparatus, yarn feeding means, a hollow cylinder, means on the cylinder coacting with said feeding means for fabricating a tubular casing, a hopper centrally disposed within the cylinder, the bottom of the hopper being adapted to communicate with the interior of the casing, means to seal the bottom of the casing whereby a bottom closure will be formed, and dispensing means adapted to discharge into the hopper the material to be packaged whereby 50 said material will be deposited within the casing over the bottom closure thereof.

45 2. In a packaging apparatus, a circular series of knitting means adapted to fabricate a tubular casing, a hopper axially disposed with respect to the knitting means, the bottom of the hopper being adapted to communicate with the interior of the casing, means to seal the bottom of the casing whereby a bottom closure will be formed, and dispensing means adapted to discharge into the hopper the material to be packaged whereby 55 said material will be deposited within the casing over the bottom closure thereof.

60 3. In a packaging apparatus, a hollow cylinder,

55 knitting elements operatively associated with the cylinder for fabricating a tubular casing, a hopper centrally disposed within the cylinder, the bottom of the hopper being adapted to communicate with the interior of the casing, gathering means engageable circumferentially with a portion of the casing for drawing said portion together, sealing means engageable with the drawn-together portion of the casing for forming a closure at such portion, and dispensing means adapted to discharge into the hopper the material to be packaged whereby 65 said material will

be deposited within the casing over the said closure thereof.

4. In a packaging apparatus, a circular series of knitting means adapted to fabricate a tubular casing, a hopper axially disposed with respect to the knitting means, the bottom of the hopper being adapted to communicate with the interior of the casing, spaced sealing means engageable circumferentially with two adjacent spaced portions of the casing for forming at the upper of said portions a bottom closure for the casing thereabove and at the lower of said portions a top closure for the casing therebelow, dispensing means adapted to discharge into the hopper the material to be packaged whereby said material will be deposited within the casing over the said bottom closure thereof, and cutting means engageable with the sealed casing at the region between the said two adjacent portions for severing the casing at said region.

5. In a packaging apparatus, two knitting machines each containing a circular series of knitting means adapted to fabricate a tubular casing, one of said machines being above the other and in axial alignment therewith whereby the casings formed thereby will be in adjacent concentric relation, a hopper axially disposed with respect to the said knitting means, the bottom of the hopper being adapted to communicate with the interior of the inner casing, means engageable circumferentially with a portion of the outer casing for sealing the two concentric casings at said portion whereby a bottom closure will be formed, and dispensing means adapted to discharge into the hopper the material to be packaged whereby said material will be deposited within the double-walled casing over the bottom closure thereof.

6. In a knitting apparatus, a plurality of hollow cylinders, knitting elements operatively associated with each of said cylinders for fabricating a tubular casing, the cylinders being in superposed relation and substantially in axial alignment whereby the casings formed will be in adjacent concentric relation, and means operatively associated with at least one of the cylinders for fastening together said concentric casings.

7. In a method of packaging, the steps of continuously knitting a tubular casing, and at predetermined times successively sealing a portion of the knitted casing to form a bottom closure, depositing the material to be packaged into the casing upon the bottom closure thereof, and severing the casing at a portion thereof below the bottom closure.

8. In a method of packaging, the steps of continuously knitting a tubular casing, and at a predetermined time sealing two adjacent portions of the knitted casing whereby there are formed at the upper of said portions a bottom closure for the casing thereabove and at the lower of said portions a top closure for the casing therebelow, depositing the material to be packaged into the casing upon the said bottom closure thereof, and severing the casing at the region between the top and bottom closures, whereby a sealed casing unit will be detached from the casing thereabove.

9. In a method of packaging, the steps of continuously knitting a tubular casing, and at a predetermined time embracing circumferentially a predetermined portion of the casing, drawing said portion together, sealing said drawn-together portion to form a bottom closure for the casing, depositing the material to be packaged into the

casing upon the bottom closure thereof, and severing the casing at a portion thereof below the bottom closure.

10. In a method of packaging, the steps of continuously knitting a tubular casing, and at predetermined times successively sealing a portion of knitted casing to form a bottom closure, depositing the material to be packaged into the casing upon the bottom closure thereof, holding the filled portion of the casing suspended from the subsequently knitted portion thereof whereby the weight of the material will operatively urge the entire casing downwardly, sealing the casing above the filled portion thereof, and detaching the sealed and filled portion of the casing from the portion thereabove.

11. In a packaging apparatus, a hollow cylinder, knitting elements operatively associated with the cylinder for fabricating a tubular casing, a hopper centrally disposed within the cylinder, feeding means adapted to discharge into the hopper the material to be packaged, gathering means below the hopper engageable circumferentially with a portion of the casing for drawing said portion together, sealing means engageable with the drawn-together portion of the casing for forming a closure at such portion, and retractile closure means at the bottom of the hopper adapted to release the material therein for deposit within the sealed casing, said feeding means, gathering means, sealing means and retractile closure means being operatively associated with said knitting elements.

12. In a packaging apparatus, a hollow cylinder, knitting elements operatively associated with the cylinder for fabricating a tubular casing, a cam ring operatively associated with the cylinder, a hopper centrally disposed within the cylinder, feeding means adapted to discharge into the hopper the material to be packaged, sealing means below the hopper circumferentially engageable with a portion of the casing and adapted to form a bottom closure therefor, and retractile closure means at the bottom of the hopper adapted to release the material therein for deposit within the sealed casing, said sealing and closure means being operatively connected to said cam ring and operable in predetermined timed relation with said knitting elements.

13. In a packaging apparatus, a hollow cylinder, knitting elements operatively associated with the cylinder for fabricating a tubular casing, rotatable yarn feeding means, a substantially cylindrical hopper centrally disposed within the cylinder, bearing means operatively associated with said yarn feeding means and the outer surface of the hopper, the bottom of the hopper being adapted to communicate with the interior of the casing, means to seal the bottom of the casing whereby a bottom closure will be formed, and dispensing means adapted to discharge into the hopper the material to be packaged whereby said material will be deposited within the casing over the bottom closure thereof.

14. In a packaging apparatus, two hollow cylinders, knitting elements operatively associated with each of said cylinders for fabricating a tubular casing, the cylinders being in superposed relation and substantially in axial alignment whereby the casings formed will be in adjacent concentric relation, a cam ring on each of said cylinders for operating said knitting elements, transmission means connecting said cam rings whereby both rings will operate simultaneously, a hopper extending downwardly into said cylinders

from a level above the upper cylinder to a predetermined level within the lower cylinder, the bottom of the hopper being adapted to communicate with the interior of the inner casing, means engageable circumferentially with a portion of the outer casing for sealing the concentric casings at said portion whereby a bottom closure will be formed, and dispensing means adapted to discharge into the hopper the material to be packaged whereby said material will be deposited within the inner casing over the bottom closure thereof.

15. In a packaging apparatus, a hollow cylinder, knitting elements operatively associated with the cylinder for fabricating a tubular casing, a cam ring operatively associated with the knitting elements, an actuator ring cooperatively connected with said cam ring and rotatably operable in predetermined timed relation therewith, a hopper centrally disposed within the cylinder, feeding means adapted to discharge into the hopper the material to be packaged, sealing means below the hopper circumferentially engageable with a portion of the casing and adapted to form a bottom closure therefor, and retractible closure means at the bottom of the hopper adapted to release the material therein for deposit within the sealed casing, cam means on said actuator ring operatively connected to said sealing means, and electro-mechanical means operatively connecting said cam ring with said closure means.

16. In a packaging apparatus, a hollow cylinder, knitting elements operatively associated with the cylinder for fabricating a tubular casing, a cam ring operatively associated with the knitting elements, an actuator ring cooperatively connected with said cam ring and rotatably operable in predetermined timed relation therewith, a hopper centrally disposed within the cylinder, feeding means adapted to discharge into the hopper the material to be packaged, sealing means below the hopper circumferentially engageable with a portion of the casing and adapted to form a bottom closure therefor, said sealing means containing wire fastening means adapted to secure a wire fastener about the casing to form said closure, cam means on said actuator ring operatively connected to said fastening means, and retractible closure means at the bottom of the hopper adapted to release the material therein for deposit within the sealed casing.

17. In a packaging apparatus, a hollow cylinder, knitting elements operatively associated with the cylinder for fabricating a tubular casing, a cam ring operatively associated with the knitting elements, an actuator ring cooperatively connected with said cam ring and rotatably operable in predetermined timed relation therewith, a hopper centrally disposed within the cylinder, feeding means adapted to discharge into the hopper the material to be packaged, gathering means engageable circumferentially with a portion of the casing for drawing said portion together, wire stapling means operatively engageable with said drawn-together portion of the casing and adapted to apply a wire staple thereabout to form a bottom closure for the casing, and means on said actuator ring for actuating said stapling and gathering means.

18. In a packaging apparatus, a hollow cylinder, knitting elements operatively associated with the cylinder for fabricating a tubular casing, a cam ring operatively associated with the knitting elements, an actuator ring cooperatively con-

nected with said cam ring and rotatably operable in predetermined timed relation therewith, a hopper centrally disposed within the cylinder, feeding means adapted to discharge into the hopper the material to be packaged, gathering means engageable circumferentially with a portion of the casing for drawing said portion together, two-wire staplers flanking said gathering means and each engageable with the casing in a region adjacent said gathering means and adapted to apply a wire staple thereabout, whereby the upper of said staplers will form a bottom closure for the casing thereabove and the lower of said staplers will form a top closure for the casing therebelow, and cam means on said actuator ring operatively connected to said staplers and said gathering means.

19. In a packaging apparatus, a hollow cylinder, knitting elements operatively associated with the cylinder for fabricating a tubular casing, a cam ring operatively associated with the knitting elements, an actuator ring cooperatively connected with said cam ring and rotatably operable in predetermined timed relation therewith, a hopper centrally disposed within the cylinder, feeding means adapted to discharge into the hopper the material to be packaged, sealing means below the hopper circumferentially engageable with a portion of the casing and adapted to form a bottom closure therefor, cutting means engageable with the sealed casing below the bottom closure thereof, and cam means on said actuator ring operatively connected to said sealing means and cutting means.

20. In a packaging apparatus, a hollow cylinder, knitting elements operatively associated with the cylinder for fabricating a tubular casing, a cam ring operatively associated with the knitting elements, an actuator ring cooperatively connected with said cam ring and rotatably operable in predetermined timed relation therewith, a hopper centrally disposed within the cylinder, feeding means adapted to discharge into the hopper the material to be packaged, sealing means below the hopper circumferentially engageable with a portion of the casing and adapted to form a bottom closure therefor, feeding means adapted to discharge into the hopper the material to be packaged, retractible closure means at the bottom of the hopper adapted to release the material therein for deposit within the sealed casing, cam means on said actuator ring cooperatively associated with said sealing and cutting means, and electro-mechanical means operatively connecting said cam ring with said feeding means and said hopper closure means.

21. In a packaging apparatus, a hollow cylinder, knitting elements operatively associated with the cylinder for fabricating a tubular casing, a hopper centrally disposed within the cylinder, the bottom of the hopper being adapted to communicate with the interior of the casing, means to seal the bottom of the casing whereby a bottom closure will be formed, dispensing means adapted to discharge into the hopper the material to be packaged whereby said material will be deposited within the casing over the bottom closure thereof, and marking means engageable with a predetermined portion of the casing for forming an identifying mark theron, said marking means being coactively associated and in predetermined timed relation with said knitting elements.

22. In a packaging apparatus, two hollow cylinders, knitting elements operatively associated

with each of said cylinders for fabricating a tubular casing, the cylinders being in superposed relation and substantially in axial alignment whereby the casings formed will be in adjacent concentric relation, label dispensing means, and guide means communicating between said dispensing means and a region between the two casings at a predetermined point above their juncture, whereby a label from said dispensing means will be fed in between the two casings, said label dispensing means being operatively associated and in predetermined timed relation with said knitting elements.

23. In a packaging apparatus, a hollow cylinder, knitting elements operatively associated with the cylinder for fabricating a tubular casing, a hopper centrally disposed within the cylinder, the bottom of the hopper being adapted to communicate with the interior of the casing, means to seal the bottom of the casing whereby a bottom closure will be formed, dispensing means adapted to discharge into the hopper the material to be packaged whereby said material will be deposited within the casing over the bottom closure thereof and urge by its weight the entire casing downwardly, and friction means in engagement with said casing opposing the action of the weight of the material whereby the tension in the casing will be reduced.

24. In a packaging apparatus, a hollow cylinder, knitting elements operatively associated with the cylinder for fabricating a tubular casing, a hopper centrally disposed within the cylinder, the bottom of the hopper being adapted to communicate with the interior of the casing, means to seal the bottom of the casing whereby a bottom closure will be formed, dispensing means adapted to discharge into the hopper the material to be packaged whereby said material will be deposited within the casing over the bottom closure thereof, and an annular forming guide member disposed within the casing below the hopper and above the sealing means and curved inwardly towards the axis of the cylinder, said guide member cooperating with the sealing means to provide a smooth bottom portion for the casing.

25. In a packaging apparatus, a hollow cylinder, knitting elements operatively associated with the cylinder for fabricating a tubular casing, a hopper centrally disposed within the cylinder, the bottom of the hopper being adapted to communicate with the interior of the casing, means to seal the bottom of the casing whereby a bottom closure will be formed, dispensing means adapted to discharge into the hopper the material to be packaged whereby said material will be deposited within the casing over the bottom closure thereof, an annular forming guide member disposed within the casing below the hopper and above the sealing means and curved inwardly towards the axis of the cylinder, said guide member cooperating with the sealing means to provide a smooth bottom portion for the casing, and annular resilient means disposed about the outer surface of the casing and frictionally holding the casing against the said guide member.

26. In a packaging apparatus, a hollow cylinder, knitting elements operatively associated with the cylinder for fabricating a tubular casing, a hopper centrally disposed within the cylinder, the bottom of the hopper being adapted to communicate with the interior of the casing, means to seal the bottom of the casing whereby a bot-

tom closure will be formed, dispensing means adapted to discharge into the hopper the material to be packaged whereby said material will be deposited within the casing over the bottom closure thereof, an annular forming guide member disposed within the casing below the hopper and above the sealing means and curved inwardly towards the axis of the cylinder, said guide member cooperating with the sealing means to provide a smooth bottom portion for the casing, and marking means engageable with the outer surface of the casing and adapted to bring it into pressing engagement with said guide member for forming an identifying mark thereon, said marking means being coactively associated and in predetermined timed relation with said knitting elements.

27. In a packaging apparatus, a hollow cylinder, knitting elements operatively associated with the cylinder for fabricating a tubular casing, a cam ring operatively associated with the knitting elements, an actuator ring cooperatively connected with said cam ring and rotatably operable in predetermined timed relation therewith, a hopper centrally disposed within the cylinder, feeding means adapted to discharge into the hopper the material to be packaged, gathering means engageable circumferentially with a portion of the casing for drawing said portion together, fastening means engageable with said drawn-together portion of the casing for forming a closure thereat, said gathering means comprising a plurality of arcuate segments circumferentially disposed about said casing, means to move said segments radially inwardly towards the axis of the cylinder, and means to retract said segments outwardly.

28. In a packaging apparatus, a hollow cylinder, knitting elements operatively associated with the cylinder for fabricating a tubular casing, a cam ring operatively associated with the knitting elements, an actuator ring cooperatively connected with said cam ring and rotatably operable in predetermined timed relation therewith, gathering means engageable circumferentially with a portion of the casing for drawing said portion together, fastening means engageable with said drawn-together portion of the casing for forming a closure thereat, said gathering means comprising a plurality of arcuate segments circumferentially disposed about said casing, a rotatably mounted annular cam plate adjacent said segments and containing a plurality of cam slots corresponding in number to said segments, each of the segments being provided with a follower in engagement with an adjacent one of said slots, means on said actuator cam adapted to rotatably actuate said cam plate from its normal position through a predetermined arc, the direction of said slots being such as to guide said followers and segments radially inwardly toward the axis of the cylinder, and means to return said cam plate to its normal position.

29. In a packaging apparatus, the combination according to claim 28, each of said cam slots containing an innermost portion extending for a predetermined distance circumferentially with respect to the cylinder axis, whereby the segments will remain stationary while the followers thereof are in engagement with said innermost portions of the cam slots.

30. In a packaging apparatus, a hollow cylinder, knitting elements operatively associated with the cylinder for fabricating a tubular casing, a cam ring operatively associated with the knit-

ting elements, an actuator ring cooperatively connected with said cam ring and rotatably operable in predetermined time relation therewith, gathering means engageable circumferentially with a portion of the casing for drawing said portion together, fastening means engageable with said drawn-together portion of the casing for forming a closure thereat, feeding means communicating with the interior of the sealed casing for depositing therein the material being packaged, cutting means engageable with the sealed casing below the said closure thereof, means on said actuator ring operatively engageable with said gathering, fastening and cutting means, said cutting means containing a rotatably mounted circular blade, a pivotally mounted arm supporting said blade, and means on said actuator ring for rotatably actuating the blade and pivotally moving said arm towards the casing.

31. In a packaging apparatus, a hollow cylin-

der, knitting elements operatively associated with the cylinder for fabricating a tubular casing, a hopper centrally disposed within the cylinder, the bottom of the hopper being adapted to communicate with the interior of the casing, means to seal the bottom of the casing whereby a bottom closure will be formed, and feeding means communicating with the hopper and adapted to deposit therein the material to be packaged, said feeding means containing an oscillating dispenser having therein two compartments, said dispenser being movable alternately to two positions whereby each of said compartments is alternately in communication with said hopper, reciprocating actuating means operatively connected with said dispenser and operable in predetermined timed relation with said knitting elements, and means to convey the material to the dispenser.

I. LAWRENCE LESAVOY.
